UNITED STATES PATENT OFFICE.

ORAL LEWIS KILLION, OF FAIRFIELD, IOWA.

COMBINATION SQUARE AND PROTRACTOR.

1,255,429.

Specification of Letters Patent.

Patented Feb. 5, 1918.

Application filed March 10, 1916. Serial No. 33,351.

To all whom it may concern:

Be it known that I, ORAL L. KILLION, a citizen of the United States, residing at Fairfield, in the county of Jefferson and State of Iowa, have invented certain new and useful Improvements in Combination Squares and Protractors, of which the following is a specification.

This invention appertains to that class of straight edges, wherein, it is desired to embody in a planing instrument an arrangement affording all the properties of the square miter and protractor combined in one.

It is also sought by the present construction, to provide an instrument capable of use without adjustment or rearrangement, which, may serve as a carpenter's square, a try-square, a miter square, for all angles, as a tool for marking double miter, for use with a plumb bob for facilitating the ascertainment of the degrees of pitch, for marking any angle of a board close up to the end without waste of material when cut, for laying out polygons or for practically any purpose wherein the user is desirous of obtaining various angles.

Among the many advantages accruing from an instrument constructed in accordance with my invention, may be mentioned the extremely simple manner in which the instrument may be operated, the fact that an angle at any degree may be marked on either side of the work to which the same is adapted for use, that the instrument may be used for marking angles of any degree contained in a straight angle on either edge of a board, out to the end thereof, consequently preventing waste of the material when sawing; finally, eliminating the intricate construction heretofore adapted for some of the above mentioned purposes and providing a tool which is exceedingly simple in construction and highly efficient in practical use.

Other improvements and novel details in the construction and arrangement of the various parts of the apparatus will be brought out more in detail in the description to follow, which, for a clear understanding of the invention should be considered in connection with the accompanying drawings, forming a part hereof, and wherein is disclosed for the purpose of illustration convenient

and satisfactory embodiments of the invention.

In the drawings:—

55

Figure 1 is a top plan; and

Fig. 2 is a fragmentary end elevation.

Referring now more particularly to the drawings, wherein like reference characters denote like or corresponding parts through the several views thereof, 1 represents an elongated straight edge member, having one end thereof beveled as at 2, and having extending therefrom and in alinement therewith, that is with the end 2, a member 3, which member may be disposed at an angle of 45° or to any position such as conditions or preference may dictate, and may be, of course, either integral therewith, or may be a separate piece and secured in some suitable manner. The straight edge 3 has arranged at its lower end an angularly disposed portion 4, which extends into engagement with the elongated straight edge 1 at a point intermediate its ends and at right angles thereto, thereby constituting the usual triangle. Positioned along both faces of the straight edge 1 and parallel with the edges thereof are two right angularly disposed strips 5 and 6. It may be mentioned that these strips 5 and 6, are in exact vertical alinement, the purpose of which will be hereinafter apparent, and are arranged slightly beyond the member 4, but in alinement therewith so as to be adjacent the meeting edges or angle of said member 4 and the elongated straight edge 1. As above intimated, this instrument as thus far described may be manufactured in one piece, striking up the strips 5 and 6, or the various constituent parts may be separate and distinct units which may be then assembled into a single, rigid construction, as described. However, the latter is preferable, due to the commercial possibility offered by this construction.

The various edges afforded by this implement may be graduated for the purposes heretofore described. For instance, the elongated straight edge is provided with, adjacent both edges, a series of figures as at 7, indicating the linear measurements, such as inches, and fractions thereof, while the 45° straight edge is provided with a series of

- graduations 8 which are similarly inscribed on both sides of the implement with the point α as a center. The graduations 8 perform the function of a protractor and in laying out angles on a board, the implement is laid against the edge of the board and rotated the required distance with the point α as a center to bring the proper one of the graduations 8 into coincidence with the edge of the board and thus obtain the required angle. The right angular straight edge has arranged thereon a series of graduations 9 inscribed thereon and indicating linear measurements, as inches, and their fractions. It is further contemplated by the invention, to apply to each side of the instrument such data as will enable the user to ascertain various measurements and angles. Data 10 and 11 is also inscribed on one surface of the implement as shown in the drawing, the purpose of the data being to enable the user of the implement to obtain the correct angles in laying out the work.
- In practical application, it will be apparent that when the device is adapted for use as a protractor, the square is merely placed upon the work and one of the strips 5 or 6 engaged with the end thereof, and by moving or turning the instrument, the end of the strip serving as a fulcrum point or center, until the edge of the work is brought into alignment with the degree desired, the proper or necessary angle is obtained by the outer end of the elongated straight edge 1. The flanges 5 and 6 also serve as means whereby the instrument may be quickly and accurately applied. It is also to be appreciated that when the device is used as a protractor, and the elongated straight edge has been adjusted to the suitable angle, that at the same time the straight edge 4 will describe an angle of 90° minus the number of degrees on the protractor.
- In laying out the angles of a polygon, the operation may be greatly expedited by referring to the scale giving the length of the

sides of the polygon of a predetermined number of sides. It may be mentioned that the straight edge 4 and the outer end of the elongated straight edge 1 constitute an efficient tri-square whereas the said elongated member serves alone in the capacity of a rule, and finally, that the members 3 and 4 together with that portion of the member 1 which they embrace affords a 45° triangle.

From the foregoing, it will be obvious to workers in this art, that I have provided an instrument which greatly excels the prior constructions of this character and have combined in a single instrument a device which may be used for the innumerable purposes offered thereby.

It will be understood that the drawings illustrate a preferred embodiment of the invention and that minor changes in this particular construction and arrangement of parts may be made in the scope of the appended claim without departing from the nature or principle of the invention.

Having thus described the invention, what I claim as new and desire to secure by Letters Patent, is;—

A square comprising a long blade and a short blade perpendicular thereto, a third blade connecting the long and short blades and inclined thereto, a flange on each side of the square at right angles thereto and in alignment with the inner edge of the long blade, the inner vertical edges of the flanges being in coincidence with the intersection of the long and short blades, one or the other of the said flange edges acting as a pivot to revolve the square at the edge of a board, and said third blade having graduations radiating from said intersection, whereby various angles may be laid off.

In testimony whereof I affix my signature in presence of two witnesses.

ORAL LEWIS KILLION.
